UNITED STATES PATENT OFFICE.

JOHANN SCHRÖDER, OF BREMEN, GERMANY, ASSIGNOR TO LANDWIRTSCHAFTLICHE MASCHINEN-GESELLSCHAFT, OF HEMELINGEN, NEAR BREMEN, GERMANY.

DEVICE FOR FIXING DRIVING ENGINES OR ELECTROMOTORS TO MACHINES TO BE DRIVEN.

Application filed January 26, 1920. Serial No. 354,295.

To all whom it may concern:

Be it known that I, JOHANN SCHRÖDER, citizen of Germany, residing at Bremen, Parkallee 27-29, Germany, have invented 5 certain new and useful Improvements in Devices for Fixing Driving Engines or Electromotors to Machines to be Driven, of which the following is a specification.

This invention relates to a device for fixing a driving engine or an electromotor to a machine to be driven such as machine-tool or the like. The device is destined essentially to be used in connection with farm machinery, such as centrifuges, churns, machines 15 for kneading butter, washing machines, mangling machines, pumps and the like. Owing to this invention the coupling of such machines with the driving engine or electromotor can be easily effected without 20 requiring much transformation of the machine and without the insertion of a special transmission. It has already been proposed to drive working machines directly from the motor by means of belt or chain-transmission. The devices of the known types 25 require however a special construction of the working machine or machine-tool in order to permit of the fixing of the motor. On the other hand the devices of known 30 types do not generally allow a secure fixing for the reason that the driving engine or the electromotor is not situated centrally with regard to the machine to be driven so that the working-machines as well as the driving 35 engine or motor suffer greatly from the shaking or from other stress.

This invention consists in providing guiding extensions of the casing of the driving engine, said extensions being situated within 40 the vertical plane of the driving shaft, designed to engage with a hub-like holder when the two machines are being connected; the driving shaft and the driven shaft being accurately in alignment the one with regard 45 to the other.

The invention further consists in a guide-sleeve mounted upon the driving shaft and designed to be fixed in a hub-like holder when the two parts are being connected. 50 Other novel features of the invention are; that one of the lateral bearings of the motor casing can serve at the same time as guide-sleeve, and that the guiding support is adjustable.

With these and other objects in view the 55 invention consists of the special combination and arrangement of parts all of which will be hereinafter fully described, claimed in the appending claims and shown in the accompanying drawings, in which; 60

Fig. 1 is a side elevation of the connecting device;

Fig. 2 is a front view of the driving motor and the improved connecting device;

Fig. 3 shows, on a larger scale, the driving 65 engine, the casing of the same being partly in section.

The driving engine or electromotor *a* has a shafting for acting upon the driving shaft *c*. The driving-shaft *c* is to be coupled in 70 the well known manner with the driven shaft *e* of a machine-tool or of a working machine for example of a centrifuge, by means of a sliding coupling sleeve *d*. In order to permit of rapidly bringing the 75 motor into the proper position with regard to the machine to be driven, a guiding-device is provided in connection with the casing *b* of the driving engine of motor *a*, which is situated in the vertical plane of the driving-shaft and serves for ensuring the proper 80 position of the two shafts *c*, *e* in alignment. The guiding device consists as shown in Fig. 3 by way of example, of a guide-sleeve *g* fixed to the casing *b* by means of screwbolts 85 *f*, the said guide-sleeve *g* being designed to be inserted into a hub-like holder *h* in which it is fixed through clamping screws *i*. This guide-sleeve *g* can form at the same time, the lateral bearing *k* of the casing *b* for the 90 driving shaft *c* or the said bearing *k* can be extended so as to form the guide-sleeve. In order to ensure an easy and proper adjustment, the holder *h* is adjustably connected 95 with the machine to be driven. This adjustable connection is effected, for example, by means of a supporting plate *l* to which the rod *m*, which carries the cylindrical holder *h*, is fixed in the following manner.

The lower part *n* of rod *m* is threaded and 100 clamped upon the plate *l* through a nut *o*. The rod *m* could however be adjustably fixed in any suitable manner in a longitudinal slot *p* of the said plate *l*.

The driving shaft *c* has a crank handle *q* 105 designed to properly regulate the ratio of speed of the machine to be driven before the motor is thrown in gear so that neither the

gear nor the motor are damaged at the start. The guide-sleeve *g* can further be bored out in any convenient manner.

It is essential for the invention that the 5 guiding devices be situated close to and within the vertical plane common to the two shafts so that thus the driving shaft and driving engine may be fixed and located as centrally as possible with regard to the 10 shaft to be driven.

I claim:

1. An improved device for fixing to the machine to be driven a driving engine or electromotor having a shafting, comprising 15 in combination an extension of the casing of the driving engine or electromotor situated within the vertical plane of the driving shaft and serving as guiding device, a lateral bearing, and a guiding holder fixed to the machine to be driven adapted to receive the said extension of the casing to secure the shafts of the driving engine and of the machine to be driven in aligned position.

2. An improved device for fixing to the 25 machine to be driven a driving engine or electromotor having a shafting, comprising in combination, the driving shaft, the casing of the driving engine or electromotor, an adjustable stand, a guide sleeve projecting 30 from said casing and mounted upon the said driving shaft, a cylindrical holder adjustably fixed to the machine to be driven for the reception of the said guide sleeve means for fixing said guide-sleeve in the said holder.

3. An improved device for fixing to the 35 machine to be driven a driving engine or electromotor having a shafting, comprising in combination, the driving shaft, the casing of the driving engine or electromotor, a guide sleeve projecting from said casing and serving as bearing for the said driving shaft, an

adjustable stand for the holder, a cylindrical holder adjustably fixed to the machine to be driven for the reception of the said guide sleeve and means for fixing said guide sleeve in the said holder.

4. An improved device for fixing to the machine to be driven a driving engine or electromotor having a shafting, comprising 50 in combination, the driving shaft, the casing of the driving engine or electromotor, a guide sleeve projecting from said casing and mounted upon the said driving shaft, a cylindrical holder adjustably fixed to the machine to be driven for the reception of the said guide sleeve means for fixing said guide sleeve in the said holder, and an adjustable stand and means for adjustably fixing the said holder to the machine to be driven.

5. An improved device for fixing to a machine to be driven a driving engine or electromotor having a shafting, comprising in combination with the driving shaft and with the casing of the driving engine or electromotor a guide sleeve projecting from said casing and serving as bearing for the said driving shaft, a cylindrical holder for said guide sleeve, means for fixing the said sleeve in the said holder, a vertical support for 70 said cylindrical holder, a threaded lower part of said vertical support, a support plate horizontally projecting from the machine to be driven having a longitudinal guide slot for the said vertical support, and a nut for adjustably fixing the said support to the said plate, substantially as described and shown and for the purpose set forth.

In testimony whereof I affix my signature in presence of two witnesses.

JOHANN SCHRÖDER.
